Primary Examiner — John Windmuller(74) *Attorney, Agent, or Firm* — Aka Chan LLP(57) **CLAIM**

The ornamental design for an umbrella with solar panels, as shown and described.

DESCRIPTION

FIG. 1 shows a perspective view of a design for an umbrella with solar panels.

FIG. 2 shows a top view of the design; and,

FIG. 3 shows a side view of the design.

The broken-lines features in the drawings represent structure or features which form no part of the claimed design.
